(57) **CLAIM**

The ornamental design for a spout connector and reinforcement ring assembly as shown and described.

DESCRIPTION

FIG. 1 is a top perspective view of the spout connector and reinforcement ring assembly with the reinforcement ring disassembled from the spout connector.

FIG. 2 is a front elevation view of the spout connector and reinforcement ring assembly of FIG. 1 with the reinforcement ring assembled on the spout connector.

FIG. 3 is a rear elevation view of the spout connector and reinforcement ring assembly of FIG. 2.

FIG. 4 is a left side elevation view of the spout connector and reinforcement ring assembly of FIG. 2.

FIG. 5 is a right side elevation view of the spout connector and reinforcement ring assembly of FIG. 2.

FIG. 6 is a top plan view of the spout connector and reinforcement ring assembly of FIG. 2; and,

FIG. 7 is a bottom plan view of the spout connector and reinforcement ring assembly of FIG. 2.

The characteristic feature of the design resides in the reinforcement ring which is removably attachable to the spout connector to reinforce the spout connector against expanding when the spout connector is removably attached to a threaded opening of a container.
